CLAIM

The ornamental design for a trouser hanger, as shown and described.

DESCRIPTION

FIG. 1 is a top perspective view of a trouser hanger, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged partial view taken from the broken circle 9 in FIG. 1; and,

FIG. 10 is an enlarged partial view taken from the broken circle 10 in FIG. 2.

The dash-dot-dot-dash lines represent the enlarged partial view regions and form no part of the claimed design.
